OPERATING MEANS FOR WINDOW STRUCTURES

Michael J. Tracy, Robertson, Mo.

Application November 6, 1946, Serial No. 708,104

10 Claims. (Cl. 268—117)

1 This invention relates generally to casement windows and more specifically to windows of this type which include operating means for adjusting the sashes of the casement windows to open and closed positions, the predominant object of the invention being to provide an improved casement window that is provided with operating means which is extremely simple in construction and operation and which provides for weather tightening the casement window and locking the sash of the window in closed position and in various open positions.

Fig. 1 is a fragmentary vertical elevation of a casement window constructed and arranged in accordance with this invention.

Fig. 2 is an enlarged, fragmentary, vertical section taken on line 2—2 of Fig. 1.

Fig. 3 is an enlarged, fragmentary, vertical section taken on line 3—3 of Fig. 1.

Fig. 4 is a horizontal section on a reduced scale and taken on line 4—4 of Fig. 1.

Fig. 5 is a horizontal section on the approximate scale of Fig. 4 and taken on line 5—5 of Fig. 1.

Fig. 6 is a fragmentary, sectional detail illustrating one of the weather tightening structures of the improved operating means of the present invention.

Fig. 7 is an enlarged, fragmentary, sectional detail taken on line 7—7 of Fig. 5.

In the drawings, wherein is shown for purposes of illustration, merely, one embodiment of the invention, A designates the improved casement window generally. The improved window structure includes a rectangular window frame 1 which is set in a window opening B formed in a wall C, said window frame being composed of top, bottom, and side frame members which are suitably joined together to provide the rectangular window frame. The particular window frame illustrated in the drawings is made up of frame members of the cross-sectional shape shown to good advantage in Figs. 2, 3, 4, and 5; that is to say, each frame member of the window frame member includes an inner leg 1a which is flush with the inner face of the wall C, an outer leg 1b which is flush with the outer face of said wall C, and a transverse leg 1c which joins the legs 1a and 1b (see Figs. 2 and 3). At one side of the window frame 1, the left-hand side as the improved window structure is illustrated in Figs. 1, 4, and 5, said window frame is provided with a pair of hinge members 2, one of said hinge members being welded, or otherwise secured, to the window frame at the top thereof and the

other of said hinge members being similarly secured to the window frame at the bottom thereof. The hinge members 2 are secured to the outer face of the window frame and extend outwardly from said frame.

Set into the sash opening of the window frame 1 is the sash 3 of the improved window structure, said sash being rectangular in shape and being composed of top, bottom, and side sash members which are suitably secured together to provide the sash. By referring to Figs. 2, 3, 4, and 5 it will be noted that the cross-sectional shape of the members which compose the window sash 3 resemble the cross-sectional shape of the members which compose the window frame 1; that is to say, each sash member includes an inner leg 3a, an outer leg 3b, and a transverse leg 3c which joins the legs 3a and 3b. The window sash has welded, or otherwise secured thereto, a pair of hinge members 4, these hinge members being shaped in accordance with the hinge members 2 and being secured to the outer face of the window sash from which they extend outwardly. The upper pair of hinge members 2 and 4 and the lower pair of hinge members 2 and 4 are hingedly secured together for movement of the hinge members 4 with respect to the hinge members 2 by means of bolt and nut assemblies 5, there being a washer 6 interposed between each related pair of hinge members, as is shown to good advantage in Fig. 2. Also, it will be noted by referring to Fig. 2, that the transverse legs 3c of the window sash 3 are spaced inwardly from the transverse legs 1c of the window frame 1 when the window sash is in its closed position, and that at this time the legs 3b of the window sash overlap and contact with the legs 1b of the window frame, while the legs 3a of the window sash contact with the legs 1a of the window frame.

Supported in a vertical position for axial rotation at the right-hand side of the window frame, as the window structure is illustrated in Figs. 1, 4, and 5, is an elongated tubular element 7. This tubular element extends from leg 1c of the bottom window frame member to the leg 1c of the top window frame member, there being supporting pins 8 seated in said legs 1c of said top and bottom window frame members and extended into the opposite end portions of the tubular element 7 for supporting said tubular element for axial rotation.

Welded, or otherwise secured to the tubular element 7 at the bottom thereof is a horizontal arm 9, said arm being disposed in the space between the lower transverse leg 1c of the window

frame 1 and the lower transverse leg 3c of the window sash 3. The arm 9 has formed integral therewith an arcuate handle element 10, the center of the curvature of said arcuate handle element being the center of the tubular element 7, and said arcuate handle element extends through an opening 12 formed through the leg 1a at the bottom of the window frame 1 (Fig. 3). Pivotally attached to the outer portion of the arm 9 by means of a pivot element 13 is an elongated connecting member 14, the opposite end of said connecting member being pivotally attached by means of a pivot element 15 to an element 16 which is secured to the transverse leg 3a at the bottom of the window sash 3. In like manner, the tubular element 7 has welded, or otherwise secured to its upper portion an arm 17 which is shaped as is the arm 9 with the exception that no arcuate handle element is extended therefrom. The arm 17 is disposed between the upper transverse leg 1c of the window frame 1 and the upper transverse leg 3c of the window sash 3, and pivotally attached to the outer portion of the arm 17 by means of a pivot element 18 is an elongated connecting member 19. At its opposite end the connecting member 19 is pivotally attached by means of a pivot element 20 to an element 21 which is secured to the upper transverse leg 3c of the window sash 3.

It is to be noted that outer portions of the arms 9 and 17 are provided with extensions 9' and 17' which are provided with inclined edges 22. Also, the window sash has secured to the inner faces of the legs 3b of said window sash located at the top and bottom of said window sash a pair of elements 23 which are provided with inclined portions 23' that are adapted to be engaged by the inclined edges 22 of the extensions 9' and 17' of the arms 9 and 17 when the window sash 3 approaches its closed position and when said window sash is in its closed position (see Figs. 4, 5, and 6). These parts of the improved window structure provide the weather tightening means of the improved structure which seal the window sash in weather-tight relation with respect to the window frame, and the precise operation of said weather tightening means will be hereinafter explained.

The arcuate handle element 10 is provided with a pivot element 24 which is secured to said arcuate handle element, a portion of said handle element being interposed between the head of the pivot element and a shoulder 24' formed thereon, as is shown in Fig. 7. The lower portion of the pivot element 24 supports a locking member 25 for pivotal movement with respect to the arcuate handle element 10, said locking member being provided with an opening through which the lower portion of said pivot element extends, and said pivot element 24 having an enlarged, annular, lower portion 24a which extends beyond the pivot opening of said locking member. The locking member 25 is shaped approximately in accordance with the arcuate handle element 10; that is to say it includes an arcuate portion 25a which underlies the arcuate portion of the handle element and a grip portion 25b which underlies a correspondingly shaped grip portion 10' formed on the handle element 10. The pivot element 24 is provided with a narrow aperture formed therein in which is anchored a flat strip 26 of spring material, and the locking member has formed therein a narrow slot 27 into which this strip of spring material extends. This strip of spring material retains the locking member 25 in the

position with respect to the handle element 10 in which it is shown in Fig. 5 where the grip portion 25b of the locking member is offset slightly from the grip portion 10' of the handle element and where the arcuate portion 25a of the locking member 25 is offset slightly relative to the arcuate portion of the handle element 10. However, for a purpose to be explained later herein, the grip portions of the locking member and the handle element may be squeezed together to overcome the force exerted by the strip of spring material 26 and thus cause said grip portions of said locking member and handle element to be aligned and to cause the arcuate portion of the locking member 25 to be aligned with the arcuate portion of the handle element 10. The locking member has formed in an edge portion thereof a plurality of notches 28 which perform a function to be hereinafter set forth.

When the sash 3 of the window structure A is in its closed position with respect to the window frame 1 an edge portion of the locking member 25 is in engagement with an edge portion of the opening 12 formed through the leg 1a at the bottom of the window frame 1, as is shown in Fig. 5, whereby the sash is locked in its closed position. Also, in the closed position of the window sash the inclined edges 22 formed on the extensions 9' and 17' of the arms 9 and 17 are in close engagement with the inclined portions 23' of the elements 23, as is shown in Figs. 4 and 5, whereby the window sash 3 is held in weather tight contact with respect to the window frame 1.

When it is desired to adjust the window sash 3 to an open position, the grip portions 10' and 25b of the handle element 10 and the locking member 25, respectively, are grasped and squeezed to cause said grip portions to be aligned with respect to each other, and to cause the arcuate portion of the locking member to be aligned with the arcuate portion of the handle element. The aligned handle element and locking member may then be moved through the opening 12 in the leg 1a at the bottom of the window frame 1, and such movement of said parts will subject the elongated, tubular element 7 to axial rotation. As a result of such rotation of the tubular element 7 the arms 9 and 17 will be swung outwardly, as indicated by dotted lines in Figs. 4 and 5, and the parallel connecting elements 14 and 19 at the top and bottom of the sash will move said sash to an open position, as is also indicated by dotted lines in Figs. 4 and 5. When it is desired to lock the window sash in one of various open positions the handle element 10 and the locking member 25 are adjusted to a position where one of the notches 28 is aligned with the edge portion 12' of the opening 12 formed through the leg 1a at the bottom of the window frame 1. The grip portions 10' and 25b of the handle element 10 and locking member 25, respectively, are then released whereupon the strip of spring material 26 will move the locking member out of alignment with respect to the handle element so as to cause the aligned notch of the locking member to embrace the edge portion 12' of the opening 12 and thereby effect locking of the sash in an open position, as is shown in Fig. 6.

It is to be noted that as the window sash is being moved toward its closed position with respect to the window frame, the inclined edges 22 of the extensions 9' and 17' of the arms 9 and 17 approach and finally engage the inclined portions 23' of the elements 23 just prior to final closing movement of the sash. This results in the window

sash being weather tightened during final movement of the sash to its closed position with respect to the window frame, as the final movement of the handle element 10 will draw the sash into tight contact with the frame because of the co-operative engagement of the extensions 9' and 17' of the arms 9 and 11, and the elements 23.

I claim:

1. A window structure comprising a window frame, a window sash, hinge means for movably supporting said window sash with respect to said window frame, said hinge means hingedly attaching one side of said window sash to a corresponding side of said window frame, and an operating means for moving said window sash with respect to said window frame, said operating means comprising a vertically disposed axially rotatable element, means associated with said window frame for supporting said axially rotatable element for axial rotation, a pair of arms fixed to said axially rotatable element for movement therewith and disposed respectively adjacent to the top and bottom of said window sash, elongated connecting members pivotally connected at corresponding ends thereof to said arms and pivotally connected at the opposite ends thereof to said window sash, and means comprising an arcuate handle element movable as a unit with one of said arms for subjecting said axially rotatable element to axial rotation.

2. A window structure comprising a window frame, a window sash, hinge means for movably supporting said window sash with respect to said window frame, said hinge means hingedly attaching one side of said window sash to a corresponding side of said window frame, and an operating means for moving said window sash with respect to said window frame, said operating means comprising a vertically disposed axially rotatable element, means associated with said window frame for supporting said axially rotatable element for axial rotation, a pair of arms fixed to said axially rotatable element for movement therewith and disposed respectively adjacent to the top and bottom of said window sash, elongated connecting members pivotally connected at corresponding ends thereof to said arms and pivotally connected at the opposite ends thereof to said window sash, and means comprising an arcuate handle element forming part of one of said arms for subjecting said axially rotatable element to axial rotation.

3. A window structure comprising a window frame, a window sash, hinge means for hingedly supporting said window sash with respect to said window frame, an operating means for moving said window sash with respect to said window frame, said operating means comprising a vertically disposed axially rotatable element, means associated with said window frame for supporting said axially rotatable element for axial rotation, a pair of arms fixed to said axially rotatable element for movement therewith and disposed respectively adjacent to the top and bottom of said window sash, elongated connecting members pivotally connected at corresponding ends thereof to said arms and pivotally connected at the opposite ends thereof to said window sash, and means comprising an arcuate handle element movable as a unit with one of said arms for subjecting said axially rotatable element to axial rotation, and a locking member associated with said handle element and adapted to lock said window sash in closed and open positions.

4. A window structure comprising a window

frame, a window sash, hinge means for hingedly supporting said window sash with respect to said window frame, an operating means for moving said window sash with respect to said window frame, said operating means comprising a vertically disposed axially rotatable element, means associated with said window frame for supporting said axially rotatable element for axial rotation, a pair of arms fixed to said axially rotatable element for movement therewith and disposed respectively adjacent to the top and bottom of said window sash, elongated connecting members pivotally connected at corresponding ends thereof to said arms and pivotally connected at the opposite ends thereof to said window sash, and means comprising an arcuate handle element movable as a unit with one of said arms for subjecting said axially rotatable element to axial rotation, and a locking member associated with said handle element and pivoted thereto and adapted to lock said window sash in closed and open positions.

5. A window structure comprising a window frame, a window sash, hinge means for hingedly supporting said window sash with respect to said window frame, an operating means for moving said window sash with respect to said window frame, said operating means comprising a vertically disposed axially rotatable element, means associated with said window frame for supporting said axially rotatable element for axial rotation, a pair of arms fixed to said axially rotatable element for movement therewith and disposed respectively adjacent to the top and bottom of said window sash, elongated connecting members pivotally connected at corresponding ends thereof to said arms and pivotally connected at the opposite ends thereof to said window sash, and means comprising an arcuate handle element movable as a unit with one of said arms for subjecting said axially rotatable element to axial rotation, a locking member associated with said handle element and pivoted thereto and adapted to lock said window sash in closed and open positions, and spring means for controlling pivotal movement of said locking member with respect to said handle element.

6. A window structure comprising a window frame, a window sash, hinge means for hingedly supporting said window sash with respect to said window frame, an operating means for moving said window sash with respect to said window frame, said operating means comprising a vertically disposed axially rotatable element, means associated with said window frame for supporting said axially rotatable element for axial rotation, a pair of arms fixed to said axially rotatable element for movement therewith and disposed respectively adjacent to the top and bottom of said window sash, elongated connecting members pivotally connected at corresponding ends thereof to said arms and pivotally connected at the opposite ends thereof to said window sash, and means comprising an arcuate handle element movable as a unit with one of said arms for subjecting said axially rotatable element to axial rotation, a locking member associated with said handle element and pivoted thereto and adapted to lock said window sash in closed and open positions, and spring means for urging said locking member toward its locking position, said handle element and said locking member being provided with related grip portions adapted to be simultaneously grasped for moving said locking member to its

unlocked position and for actuating said sash operating means.

7. A window structure comprising a window frame, a window sash, hinge means for hingedly supporting said window sash with respect to said window frame, an operating means for moving said window sash with respect to said window frame, said operating means comprising a vertically disposed axially rotatable element, means associated with said window frame for supporting said axially rotatable element for axial rotation, a pair of arms fixed to said axially rotatable element for movement therewith and disposed respectively adjacent to the top and bottom of said window sash, elongated connecting members pivotally connected at corresponding ends thereof to said arms and pivotally connected at the opposite ends thereof to said window sash, and means comprising an arcuate handle element movable as a unit with one of said arms for subjecting said axially rotatable element to axial rotation, a locking member associated with said handle element and pivoted thereto and adapted to lock said window sash in closed and open positions, and spring means for urging said locking member toward its locking position, said handle element and said locking member being provided with related grip portions adapted to be simultaneously grasped for moving said locking member to its unlocked position and for actuating said sash operating means, and said locking member being provided with portions adapted to engage a part of said window frame for locking said window sash in closed and open positions.

8. A window structure comprising a window frame, a window sash, means for movably supporting said window sash with respect to said window frame, an operating means for moving said window sash with respect to said window frame, said operating means comprising a vertically disposed axially rotatable element, means associated with said window frame for supporting said axially rotatable element for axial rotation, a pair of arms fixed to said axially rotatable element for movement therewith, elongated connecting members pivotally connected at corresponding ends thereof to said arms and pivotally connected at the opposite ends thereof to said window sash, and means for subjecting said axially rotatable element to axial rotation, and weather tightening means for drawing said window sash into weather tight engagement with relation to said window frame when the window sash is in its closed position.

9. A window structure comprising a window frame, a window sash, means for movably supporting said window sash with respect to said window frame, an operating means for moving said window sash with respect to said window frame, said operating means comprising a vertically disposed axially rotatable element, means

associated with said window frame for supporting said axially rotatable element for axial rotation, a pair of arms fixed to said axially rotatable element for movement therewith, elongated connecting members pivotally connected at corresponding ends thereof to said arms and pivotally connected at the opposite ends thereof to said window sash, and means for subjecting said axially rotatable element to axial rotation, and 5 weather tightening means for drawing said window sash into weather tight engagement with relation to said window frame when the window sash is in its closed position, said weather tightening means comprising extensions formed on 10 said arms, and elements fixed to said window sash into engagement with which said arm extensions move as the window sash approaches its closed position.

10. A window structure comprising a window frame, a window sash, means for movably supporting said window sash with respect to said window frame, an operating means for moving said window sash with respect to said window frame, said operating means comprising a vertically disposed axially rotatable element, means associated with said window frame for supporting said axially rotatable element for axial rotation, a pair of arms fixed to said axially rotatable element for movement therewith, elongated connecting members pivotally connected at corresponding ends thereof to said arms and pivotally connected at the opposite ends thereof to said window sash, and means for subjecting said axially rotatable element to axial rotation, and 25 weather tightening means for drawing said window sash into weather tight engagement with relation to said window frame when the window sash is in its closed position, said weather tightening means comprising extensions formed on 30 said arms which are provided with inclined faces, and elements fixed to said window sash provided with inclined portions into engagement with which the inclined faces of said arm extensions move as the window sash approaches its closed position.

45 MICHAEL J. TRACY.
